Patented Aug. 19, 1919.

UNITED STATES PATENT OFFICE.

ANTONIO MENDES TEIXEIRA, OF IPANEMA, SÃO PAULO, BRAZIL.

ELECTRICAL FURNACE.

1,313,761.

Specification of Letters Patent. Patented Aug. 19, 1919.

Application filed November 7, 1918. Serial No. 261,505.

To all whom it may concern:

Be it known that I, ANTONIO MENDES TEIXEIRA, a citizen of the United States of Brazil, residing at Ipanema, São Paulo, Brazil, have invented certain new and useful Improvements in Electrical Furnaces, and I do hereby declare the following to be a full, clear, and exact description of the invention, such as will enable others skilled in the art to which it appertains to make and use the same.

My invention relates to improvements in furnaces used in the reduction or treatment of iron or other ores, and the objects of my invention are to carry out in a single apparatus the reduction of the ore, and the refining of the molten metal so reduced.

In the case of a furnace for the manufacture of steel, the ore is reduced in the presence of carbon, the excess carbon is removed from the iron, and the steel is refined, as will be hereinafter described.

The apparatus may be used also to make pig iron, or iron or steel alloys, or to treat and refine the ores of other metals.

As part of the invention I purpose to effect the above mentioned operations simultaneously by means of the internal movements of the charge and of the molten metal, through proper arrangements of the apparatus hereinafter described.

The invention is specially intended to carry out the operations aforesaid continuously and on a large scale.

In order to provide for the continuous operation of the furnace it is important to provide for easy access to the various parts of the furnace likely to become clogged up or otherwise rendered inoperative, and also to provide for convenience in replacing or repairing those parts of the furnace that are likely to become worn out, or prove defective under the severe conditions to which such apparatus is necessarily subjected.

It is specially desirable that such repairs or replacements should be feasible, as far as possible, without throwing the entire apparatus out of operation, or interfering materially with the continuous operation of the device as a whole.

I attain these objects by the furnace illus-

trated in the accompanying drawing, in which like parts are indicated by similar reference symbols throughout the several views, and in which:

Figure 1 is a vertical section of the entire furnace;

Fig. 2, two half cross-sectional plan views of the furnace, showing in the upper half of the figure a section along the line 2—2 of Fig. 1; and in the lower half of the figure a section along the line 2^a—2^a of Fig. 1;

Fig. 3, is a vertical section of one of the open hearth electric furnaces and along the broken line 3—3 of Fig. 2; and

Fig. 4 is a view, on a smaller scale, partly in section and partly in plan, of a modified form of apparatus.

The drawings show an ordinary shaft furnace connected at its base to a series of open hearth electric furnaces, constructed as will be hereinafter described.

Three electric furnaces are shown, but the number and arrangement of these electric furnaces may be varied to suit the requirements of the specific apparatus.

Referring first to Figs. 1 to 3, A represents a shaft furnace of the usual well known type provided with a charging hopper a, and the slope a' near the bottom and the bottom opening a².

B represents the blast pipe connected to the opening in the manifold B' which is connected to the twyers b operating in the usual way.

C represents the escape pipe for the gases located near the top of the furnace. The shaft furnace A rests on the refractory support D, perforated as at d to register with the opening a² in the bottom of the furnace, and this rests on the partition blocks E of refractory material. The hearth of the central shaft furnace is connected by the passages f with the various open hearths F', F² and F³ provided in the mass of refractory material F. These hearths are connected together by side passages f', and the bottom of these passages is at higher level than the bottom of the individual hearths, for reasons which will be hereinafter described.

The group of hearths is surrounded by a wall of refractory material F sheathed with

metal G'. In this wall are the tap-holes g to draw off the slag, and g' to draw off the molten metal.

The parts E, F and G just referred to, and the parts supported thereby rest on a suitable foundation H of concrete, or other suitable material. The tops of the respective open hearths are closed by suitable roofs J provided with stuffing boxes i to permit the passage therethrough of the electrodes L. The tops of the passages f' are also provided with roofs K, which roofs are provided with openings k^o, closed by the doors k, through which openings charcoal, coke, oil or other materials for reducing or refining or for making alloys may be supplied to the electric furnaces when desired.

The electrodes L are supplied with current of any suitable number of phases from the conductors L', and may be carried off in the usual way through the opposite electrodes, or through the neutral connection L^o for star connected three phase circuits, or in any other convenient way. The method of applying and carrying off the currents not being part of my present invention will not be further described herein, except that the number of electrodes may vary according to the phases of the current; but it is preferable to use one electrode or a neutral in the hearth of each electric furnace corresponding to each vertical electrode or group of electrodes. The electrodes should enter the furnaces in the vertical position, and should be spaced a sufficient distance from the slope of the ore, so that they neither run the risk of being broken by the falling down of the charge nor of being destroyed through contact with metallic oxid.

The electrodes are adjustably suspended by the cords M from the arms N carried by the stanchions N' of the frame work of the apparatus, or in any convenient way.

In order to secure access to any one of the electric furnaces, the electrodes may be withdrawn from that furnace, and the roof may be lifted off.

In the same way in order to secure access to the parts around the side passages f', the roofs K may be removed, if access through the doors k is not sufficient.

In the modification shown in Fig. 4, instead of there being a single outer wall, as shown at G in Figs. 1 and 2, each electric furnace forms a separate removable unit, the two being connected together by removable connecting blocks and also removably connected to the base of the central shaft furnace. Thus, for instance, each electric furnace P consists of a separate removable mass of refractory material provided on those parts away from the heat of the furnace with metal sheathing p, which is flanged at the ends as at p' or connected in

other convenient ways, and the two adjacent electric furnaces are connected together by the removable blocks Q having their faces away from the furnace also covered with metal sheathing which metal sheathing is flanged as at q' to be bolted to the adjacent flanges p', or other suitable connection, the partition blocks E^o, at the base of the central shaft furnace are also sheathed as at e, and the sheathing is flanged at e' to be bolted to the adjacent flanges p' of the electric furnace P.

There is thus formed an air space R between the blocks E^o and Q and the adjacent hearths P. Thus it will be seen that any one of the furnaces may be removed, the corresponding passages q^o and f being closed and the apparatus continue to operate with one or more of the remaining furnaces; or one furnace can be put out of operation by closing up the adjacent passages q^o and f.

The carbon or other material may be inserted with the charge in the central shaft furnace, or the carbon or other reducing and refining materials, or materials used for making alloys may be inserted through the doors k.

As the charge in the shaft furnace is heated up the metal melts and flows down and assumes the same level in the various open hearth electric furnaces, where the process of refining or making the alloy is carried on, the position of the electrodes being controlled in the usual well known way, and the current being also controlled as desired, as is well known in the art.

The hot gases generated in the electric furnaces, having no other way to escape, will enter the opening a^o in the bottom of the shaft furnace, and will rise up through the charge, accelerating the fusion and reducing the ore.

The heat generated in the hearth of the electric furnaces is transmitted to the charge in the shaft by the gases from the hearth and by the molten metal, which has immersed in it the bottom of the column of the charge. Thus, the molten metal in the electric furnaces and in the bottom of the shaft is intercommunicating, and when the metal is drawn off from one of the furnaces, the molten metal from the other furnaces has to run through the partially reduced metal at the bottom of the shaft, thus decarbonizing the refined metal.

In case of an obstruction in any of the passages f, the highly heated molten metal from the adjacent electric furnaces may be made to flow through the lateral channels into the electric furnace that has been blocked up by rising the level of the molten metal, and so the melting or displacement of the solid material, which is the prime cause of the obstruction, is effected by means of

the molten metal acting on both sides of the obstruction. To secure this result it is desirable that the highest elevation in the bottom of the channel should be between the maximum and the normal levels of the molten metal in the entire system.

Any coke or charcoal inserted through the doors *k* will float on the melted slag, and will have the effect of preventing the contact of the electrodes with the oxidizing slags, and will reduce the CO₂ to CO, thus causing the electrodes to wear longer. In the cases of excessive heat under the roofs of the several electric furnaces, suitable means may be provided for cooling the same, such, for instance, as carrying part of the gases down from the pipe C, as is well known in the art, or by inserting oil through the doors *k*, or other suitable cooling means may be adopted, if desired.

It will be obvious that various modifications might be made in the herein described apparatus and in the construction, combination and arrangement of parts which could be used without departing from the spirit of my invention, and I do not mean to limit the invention in such details except as particularly pointed out in the claims.

Having thus described my invention what I claim and desire to secure by Letters Patent of the United States is:—

1. The combination with a central shaft furnace, of a group of electric furnaces surrounding the base of the shaft furnace, and connected with one another through the hearth of the shaft furnace, and also by means of lateral channels located exterior of the hearth of the shaft furnace, substantially as described.

2. The combination with a central shaft furnace, of a group of electric furnaces surrounding the base of the shaft furnace, and connected with one another through the hearth of the shaft furnace, and also by means of lateral channels located exterior of the hearth of the shaft furnace, and each electric furnace being provided with a separate removable roof, substantially as described.

3. The combination with a central shaft furnace, of a group of electric furnaces surrounding the base of the shaft furnace, and connected with one another through the hearth of the shaft furnace, and also by means of lateral channels located exterior of the hearth of the shaft furnace, and each electric furnace being provided with a separate removable roof, and each of said channels being provided with a separate roof, with doors in said roof for permitting the insertion of reducing, decarbonizing, refining and alloying materials, substantially as described.

4. The combination with a central shaft

furnace, of a group of electric furnaces surrounding the base of the shaft furnace, and connected with one another through the hearth of the shaft furnace, and also by means of lateral channels located exterior of the hearth of the shaft furnace, the said lateral channels being shallower than the hearth of the various electric furnaces and the bottom of the shaft furnace, substantially as described.

5. The combination with a central shaft furnace, of a group of electric furnaces surrounding the base of the shaft furnace, and connected with one another through the hearth of the shaft furnace, and also by means of lateral channels located exterior of the hearth of the shaft furnace, the said lateral channels being shallower than the hearth of the various electric furnaces and the bottom of the shaft furnace, substantially as described.

6. The combination with a central shaft furnace, of a group of electric furnaces surrounding the base of the shaft furnace, and connected with one another through the hearth of the shaft furnace, and also by means of lateral channels located exterior of the hearth of the shaft furnace, the said lateral channels being shallower than the hearth of the various electric furnaces, and each electric furnace being provided with a separate removable roof, and each of said channels being provided with a separate roof, with doors in said roof for permitting the insertion of materials into the electric furnaces, substantially as described.

7. The combination with a central shaft furnace, of a group of electric furnaces surrounding the base of the shaft furnace, and connected with one another through the hearth of the shaft furnace, and also by means of lateral channels located exterior of the hearth of the shaft furnace, and the various electric furnaces being included in an outer wall of refractory material, substantially as described.

8. The combination with a central shaft furnace, of a group of electric furnaces surrounding the base of the shaft furnace, and connected with one another through the hearth of the shaft furnace, and also by means of lateral channels located exterior of the hearth of the shaft furnace, and each electric furnace being provided with a separate removable roof, and the various electric furnaces being included in an outer wall of refractory material, substantially as described.

9. The combination with a central shaft furnace, of a group of electric furnaces surrounding the base of the shaft furnace, and connected with one another through the hearth of the shaft furnace, and also by means of lateral channels located exterior of

- the hearth of the shaft furnace, and each electric furnace being provided with a separate removable roof, and each of said channels being provided with a separate roof, 5 with doors in said roof for permitting the insertion of refining or other material, and the various electric furnaces being included in an outer wall of refractory material, substantially as described.
10. 10. The combination with a central shaft furnace, of a group of electric furnaces surrounding the base of the shaft furnace, and connected with one another through the hearth of the shaft furnace, and also by 15 means of lateral channels located exterior of the hearth of the shaft furnace, the said lateral channels being shallower than the hearth of the various electric furnaces, and the various electric furnaces being included in an outer wall of refractory material, and each electric furnace provided with vertical electrodes far apart from the reducing shaft, thus out of contact with the slope of the charge, substantially as described.
11. The combination with a central shaft furnace, of a group of electric furnaces surrounding the base of the shaft furnace, and connected with one another through the hearth of the shaft furnace, and also by means of lateral channels located exterior of the hearth of the shaft furnace, the said lateral channels being shallower than the hearth of the various electric furnaces, and the various electric furnaces being included in an outer wall of refractory material, substantially as described.

ANTONIO MENDES TEIXEIRA.
